BINDING POST STRUCTURE

Albert M. Pichitino, Waseca, Minn., assignor to E. F. Johnson Company, Waseca, Minn., a corporation

Application July 19, 1956, Serial No. 598,913

5 Claims. (Cl. 339—129)

This invention relates to binding posts, and more particularly to a binding post structure adapted to be mounted upon an electrical instrument panel.

It is an important object of the invention to provide an improved binding post of simplified construction which will be inexpensive to manufacture and easy to install.

Another object of the invention is to provide a special body portion for insertion through a panel opening which eliminates the necessity of extra parts such as sealing washers and furnishes increased efficiency in the mounting and operation thereof.

A further object of the invention is to provide a binding post structure in which the thumb nut is so made and the assembly steps are so arranged as to captivate the thumb nut without requiring any additional machine steps, which captivation prevents the thumb nut from being accidentally or deliberately removed from the stud after the binding post is manufactured and assembled.

These and other objects and advantages of my invention will more fully appear from the following description, made in connection with the accompanying drawings, wherein like reference characters refer to the same parts throughout the several views and in which:

Figure 1 is a fragmentary vertical section of a typical panel within which is mounted my binding post structure;

Figure 2 is a vertical section of the binding post structure, portions of the stud member being shown in full line;

Figure 3 is an end view of the binding post taken in the direction of the arrows 3—3 in Figure 2;

Figure 4 is another vertical section of the binding post taken on the line 4—4 of Figure 2; and

Figure 5 is still another vertical section taken through the body portion of the binding post on the line 5—5 of Figure 2.

With continued reference to the drawing, and particularly to Figures 1 and 2, my binding post structure comprises generally a stud 10 to which is secured a binding post body 11 and which bears a shiftable dielectric binding means 12.

The stud 10 is an elongated member unitarily constructed of conducting metal and having an intermediate portion 13 through which is formed an opening 14 adapted to receive the terminal end of a connecting wire (not shown). The stud 10 further has an enlarged threaded head 15 which is coaxially formed with the intermediate portion 13 and which is provided with a bore 16 which may be utilized as a receptacle for an electrical plug. A bearing shoulder 17 is integrally formed with the enlarged head 15 and interconnects with the intermediate portion 13. Immediately adjacent the intermediate portion 13 is a reduced shank 18 with a knurled area 19 and a threaded area 20 as shown in Figure 2. The juncture of the intermediate portion 13 and the shank 18 provides a shoulder 21 which defines the positioning of the opening 14 when the binding post is mounted in a panel. The extreme terminal end of the conducting stud 10 provides an axial soldering means 22, the latter of which may have

2

a further reduced axial portion 23 and a head 24, as shown. It will be noted that the threaded head 15 is considerably larger in cross section than the intermediate area 13. The shank portion 18 and other parts of the elongated stud member integrally formed outwardly of the intermediate portion are all of a lesser cross sectional area than that of the intermediate stud portion 13.

The binding post body 11 is constructed of dielectric material such as nylon and comprises, in turn, an enlarged portion such as the annular abutment 25 and integrally formed therewith at a position more remote from the opening 14, a threaded reduced and tubular portion 26. The outer end of the threaded tube 26 terminates at 27 which leaves exposed the soldering terminal 22, as shown. 10 The innermost portion of the enlarged abutment 25 may be provided with a circular recess 28 into which is received a metallic washer 29. The binding post body 11 and the washer 29 are rigidly secured against the shoulder 21 and in contact with the knurled area 19, as shown. A nut 30 is drawn up upon the threaded reduced portion 20 so as to further secure the binding post body 11 in its mounted relation with stud 10. The binding post body is provided with longitudinal cut portions 31 which render the threaded portion 26 unsymmetrical and capable of being inserted in an opening 32 of the same general configuration in an instrument panel 33, as shown in Figure 1. The binding post body is thus prevented from turning and the clamping nut 34 which is threadedly mounted upon the binding post will have sufficient contact with the threaded area 26 to firmly mount and hold the binding post body in position, as shown in Figure 1.

Dielectric securing means such as thumb nut 12 is provided with a fluted exterior surface 35 and an internal bore 36 which extends through the cap and is reduced to a smaller axial opening 37 at the inner end thereof. An intermediate shouldered abutment 38 may be formed within the thumb nut 12 so as to interfit with the abutment 17 when the thumb nut is in the position shown in Figure 2. The innermost annular face 39 of the thumb nut 12 is adapted to shift inwardly toward the opening 14 and to firmly clamp or bind a conducting terminal 40 when positioned therein, as shown in Figure 1. An electrical circuit may thus be established through the conducting terminal 40 and the stud 10 while maintaining metallic parts virtually shielded and covered. The other conducting lead 41 may be soldered to the soldering terminal 22 or clamped by retaining nut 30 if so desired.

In the assembly of the binding post structure, the elongated metallic stud member is inserted into the axial bore 36 formed in thumb nut 12 and the thumb nut is threadedly engaged with the enlarged threaded head 15 with the reduced bore or opening 37 closely surrounding the intermediate stud portion 13. Since all of the parts 55 of the elongated stud 10 between the shoulder 17 and the outer end of the soldering terminal 22 are of a lesser diameter than that of the reduced bore 37, it becomes possible to captivate the thumb nut during the assembly 60 of the binding post structure. It will be observed that turning the thumb nut 12 so as to retract the annular face 39 from the opening 14 will finally cause the abutment 38 and forward portion at the reduced bore 37 to come in contact with the enlarged head portion 15 and bind thereagainst. This method of captivation obviates a machine operation which would provide an abutment 65 associated with the outer ends of the stud and thumb nut as is commonly done in the art. When the thumb nut 12 is advanced toward the opening 14, the threaded head 15 remains shielded by the dielectric thumb nut 12 even in its most advanced position. Since the thumb nut has an open-ended bore 36, access is retained to the receptacle bore 16 formed within the enlarged head 15 at all times.

After the thumb nut 12 has been mounted upon the stud 10, the metallic washer or ring 29 is positioned against the shoulder 21 and the entire unitary binding post body is forced over the knurled area 19 until it firmly contacts the washer 29 and abutment 21. The retaining nut 30 may then be drawn up tightly on the threaded area 20 to contact the end 27 of the binding post body and thereby rigidly hold the body in mounted relation with the stud members. When utilized in a panel structure, the opening 32 is formed so as to assume the shape of the cut-away threaded area of the body, as shown in Figure 5. The clamping nut 34 is then secured in place and the entire stud and binding post body members are firmly and rigidly retained against rotation in panel 33. Thumb nut 12 may be advanced and retracted without danger of removing the thumb nut from the stud. As previously pointed out, when a conductor terminal 40 is placed in the opening 14, the thumb nut may be drawn up tightly thereagainst and will shield the metallic parts. Since the enlarged head 25 of the binding post body is also constructed of dielectric material and the metallic washer 29 is countersunk therein, there is very little opportunity for accidentally coming into contact with a wire of high voltage which may be secured to the binding post. Because the entire binding post body is unitary and constructed of dielectric material, it is possible to mount the binding post on metallic panels 33 while maintaining the conducting stud out of electrical contact therewith. The features and benefits of my binding post structure are obtained while simplifying the construction and assemblage thereof.

It will, of course, be understood that various changes may be made in the form, details, arrangement and proportions of the parts without departing from the scope of my invention.

What I claim is:

1. A binding post structure adapted to be mounted in an opening through a panel comprising, an elongated electrically conductive stud having a connector opening laterally disposed therethrough at a position intermediate the ends thereof, a binding post body constructed of dielectric material secured about said stud conductor intermediate said connector opening and one end thereof, said binding post body having an enlarged portion adjacent said opening and more remotely therefrom a reduced portion adapted to extend through a panel opening, a clamping element mounted on said binding post body and adapted to oppose the enlarged portion in compressing the walls of a panel when mounted thereon, and dielectric means mounted on said stud intermediate the connector opening and the other end thereof and being shiftable on said stud toward the connector opening for securing a connector terminal therein.

2. A binding post structure adapted to be mounted in an opening through a panel comprising, an elongated electrically conductive stud having a connector opening laterally disposed therethrough at a position intermediate the ends thereof, a binding post body constructed of dielectric material secured about said stud conductor intermediate said connector opening and one end thereof, said binding post body having an annular shouldered abutment

adjacent said opening and a threaded reduced portion integrally formed therewith extending away from said opening and adapted to be inserted in a panel opening, a clamping nut threadably mounted on said reduced body portion and adapted to be drawn up in compressing relation with the walls of a panel when mounted thereon, and dielectric means mounted on said stud intermediate the connector opening and the other end thereof and being shiftable on said stud toward the connector opening for securing a connector terminal therein.

3. The subject matter set forth in claim 2, wherein the threaded reduced portion of the dielectric body is longitudinally cut away in part for keying said body in a panel when mounted therein and thereby preventing rotation of the post in mounted condition.

4. A binding post structure adapted to be mounted in an opening through a panel comprising, an elongated electrically conductive stud having a connector opening laterally disposed therethrough at a position intermediate the ends thereof, said stud further having an enlarged head at one end and a reduced terminal at the other end thereof, a binding post body constructed of dielectric material secured about said stud conductor intermediate said connector opening and the terminal end thereof, said binding post body having an enlarged portion adjacent said opening and more remotely therefrom a reduced portion adapted to extend through a panel opening, a clamping element mounted on said binding post body and adapted to oppose the enlarged portion in compressing the walls of a panel when mounted thereon, and dielectric means mounted on the enlarged head of said stud and in shielding relation therewith, said dielectric means being shiftable on said stud toward the connector opening for securing a connector terminal therein.

5. A binding post structure adapted to be mounted in an opening through a panel comprising, an elongated electrically conductive stud having a connector opening laterally disposed therethrough at a position intermediate the ends thereof and further having an enlarged threaded head at one end and a reduced terminal at the other end, a binding post body constructed of dielectric material secured about said stud intermediate said connector opening and the terminal end thereof and having an enlarged end adapted to seal marginally about an opening through a panel, a clamping element mounted on said binding post body and adapted to oppose the enlarged portion in compressing relation when mounted on the wall of a panel, and a threaded dielectric thumb nut having an axial opening reduced at one end thereof, said reduced end opening being larger than the cross section of both said terminal and said intermediate portion of the stud but smaller than said enlarged threaded head whereby the thumb nut may be mounted on the stud over the terminal and intermediate portion and threadably engaged with the stud head in captivated condition prior to the mounting of the winding post body upon the stud conductor.
